(57) **CLAIM**

An ornamental design for hand wrap as shown and described.

DESCRIPTION

FIG. 1 is an isometric top, right side view of a hand wrap; FIG. 2 is an isometric top, right side view of the hand wrap of FIG. 1;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a top plan view of the hand wrap of FIG. 1 shown in an open position; and,

FIG. 10 is a bottom plan view of the hand wrap of FIG. 1 shown in an open position.

The broken lines depict environmental structure and form no part of the claimed design. In FIG. 2, the regions that are depicted as completely enclosed by broken lines also form no part of the claimed design.
